6 Claims. (Cl. 154—83)

This invention relates generally to packaging material and more particularly to improvements in overlap joints and the method of forming the same for corrugated paper.

The continuous jointing of sheets of packaging type paper with heavy surface irregularities, for example, double corrugated cardboard, for the production of protective tubes for bottles, fluorescent tubes or the like is generally effected in one of the following ways:

- (1) By overlapping the edges of the tubes and stitching these edges together with metallic stitches.
- (2) By overlapping the edges of the tubes and securing their edges together with an adhesive.
- (3) By stitching together butt joined edges.
- (4) By the application of a gummed strip of paper to the butt joined edges.
- (5) By applying an adhesive to the engaging edges of a butt joint.

Each of the above mentioned methods has well defined disadvantages or limitations, especially with regard to the thickness of the materials joined, which is usually rather substantial.

With the first method, apart from the disadvantage of forming an unsightly and protruding rib, it has the disadvantage of localizing the tensional forces, with a risk of breakage of the paper at the position of the metal stitches.

With the second method, the second of the above mentioned risks is eliminated, but the unsightly heavy rib remains; in addition there is a weakening of the joint because of the difficulty of effecting a good jointing of the two surfaces in contact due to the nature of the corrugated form of the material.

With the third method the joint is very strong, but in turn it is very unsightly as the stitching in order to have strength has to take in a couple of corrugations on each side of the joint, thus forming a rigid rib.

With the fourth method the unsightly rib is eliminated, but an almost equally unsightly strip of paper is provided, which is not strong when under tension and is difficult to apply due to the corrugated form of the material to be joined.

With the fifth method the joint is satisfactory from an aesthetic point of view, but the joint is not resistant to tensile stress since the contact surface is reduced to the thickness of the material. Moreover this type of joint provides a surface which is broken by the corrugated nature of the material.

The object of the present invention is to provide a new and improved type of joint and method of making the same which eliminates all the disadvantages of the other joints and methods of forming the same while retaining the advantages of strength and sightliness.

The joint according to this invention is characterised in that it is made by overlapping a longitudinal edge of the corrugated material which has been previously cut to size onto the opposite edge of the corrugated material which has been suitably flattened to remove the ridges from the material. Preferably the flattened sur-

2

face of the longitudinal edge of the material has been also folded and knurled.

A joint of this type has the following advantages:

- (1) A large contact surface for the jointing.
- (2) Better adhesive effect for the adhesive solution due to flattening of the surfaces in contact.
- (3) Continuity of the pattern formed by the corrugations at the joint without alteration of the spacing or pitch of the corrugations.
- (4) Uniformity of thickness of the finished tube without the formation of a rigid rib at the joint.
- (5) Flexibility at the joint, that is, it is able to adapt itself to the shape of the object which is being protected.

15 Tubes joined with this system or method (when a suitable adhesive is applied which may even be the economical sodium silicate) are very resistant to tensional forces imparted to them during use, such as when a glass bottle or tube is forced into the cardboard tube; further, they are completely satisfactory as far as the aesthetic point of view is concerned because of the uniformity of the thickness of the tube and the continuity of the corrugation pattern.

The invention includes also a process for producing an improved joint.

This invention will be described in detail in connection with the attached drawings, in which:

Figure 1 is a schematic view in perspective of a corrugated tube of pliable material which has been joined according to the invention.

Figure 2 is a schematic view showing a rectangle of pliable corrugated paper to be joined after flattening, folding and knurling of an edge.

Figure 3 is an enlarged detail view of a flat, knurled and folded edge as seen in cross section.

Figure 4 is a view showing schematically and in perspective the means forming a part of an apparatus adapted to produce tubes with joined edges in accordance with the invention.

40 For the sake of simplicity, during this description, the material being joined which may be single or double sided pliable corrugated material such as paper having a plurality of ridges and furrows will be referred to as corrugated material.

45 The joint, according to this invention (Fig. 1) comprises an edge 1 of a sheet of corrugated material *a* overlapped and gummed in position at corrugations 3 to an opposite flattened edge 2.

The width of the flat edge 2 determines the number 50 of corrugations 3 to which it can adhere, and thus the greater or less strength of the joint.

Moreover, extremity 4 of the edge 1 is gummed to side 5 of the first existing corrugation of the part of the flat edge 2, and thus, apart from increasing the strength of 55 the joint, assures continuity of the pattern made by the corrugations and assists in giving a slight finish.

Another characteristic of the joint consists in the fact that the flat edge 2 is also knurled (Fig. 2) to compensate for the tendency of the cardboard or paper forming the corrugated material *a* to lengthen in width under the flattening action and to counteract the tendency of the two sheets of paper of which the corrugated material is usually made to separate due to the loss of the corrugated form on the flattened part.

60 To avoid separation of the two sheets composing the corrugated material the extreme edge of the flat section 2 (Fig. 3) can be bent over itself before the knurling action to form a fold 6 holding the two sheets together.

In the process for forming tubes of corrugated material, joined according to this invention, the rectangle of corrugated material (Fig. 2) is first subjected to an 70 operation, generally carried out by the machine which

effects the jointing. This operational step comprises flattening edge 2 along the width of some (generally 3) main corrugations 3. The fundamental purpose of this operation is to provide a sufficiently flat surface which allows good adhesion without appreciably increasing the thickness of the joint.

Later the extreme surface of the edge 2, generally the portion corresponding to the last corrugation 3, is bent over itself, forming the fold 6 (Fig. 3). This operation avoids separation of the two sheets making up the corrugated material when the material used is of this type.

Immediately after this latter operation the flattened edge 2 is knurled with any suitable knurling pattern 7. The knurling pattern must be designed to keep the edge 2 flat and of negligible thickness. The knurling pattern 7 further functions to keep the two sheets of paper forming the corrugated material together, and to maintain correct length of the paper which would otherwise tend to lengthen to some length greater than that of the original sheet of corrugated material α .

In a later operation, the flattened and knurled edge 2 and the external edge 4 of the opposite edge 1 are covered with an adhesive coating.

During the next step of folding round the rectangle of corrugated material α , the edge 1 is brought over the flattened and knurled edge 2 (Fig. 1). As evident from Fig. 1 of the drawing edge 4 of the material is formed along one of the ridges of the corrugated material. This edge is obtained by bisecting a ridge so as to form a plane surface which is later placed, as shown in Fig. 1, along the side 5 of the first ridge of the corrugations on the flattened edge 2 side of the material.

With the help of suitable heating above and below the joint region a rapid adhesion is effected of the corrugations 3 on the flattened and knurled edge 2 and of the edge 4 on the side 5 of the corrugation 3.

This results in a tube having a joint which is very resistant to tensional forces to which it could be subjected during its use, for example, when the object to be protected (such as bottles, fluorescent tubes etc.) is forced into it. At the same time the tube formed by the practice of this invention is aesthetically satisfactory due to the uniformity of spaced ridges and furrows of the corrugated material at the joint region.

The apparatus for producing tubes with edges joined as described hereinabove and as illustrated in Fig. 4 comprises upper and lower flattening plates 8 and 9, respectively, with the lower plate lowered with respect to its normal position to show the conformation of the flattening plate. A pair of knurling rollers 10 and 11 follow in the path of operation where the flattened edge is knurled prior to entering the forming tube 12 which cooperates with inner supporting tube 13. The side of the knurled edge 3 which is glued to the edge 1 of the corrugated material or the edge 1 is provided with adhesive material in any convenient manner.

While only one embodiment of the invention has been described, it will be obvious to those skilled in the art that many variations and modifications can be made without departing from the scope of the invention.

I claim:

1. The method of joining edges of pliable and expandible corrugated material having ridges and furrows on both sides which comprises flattening a plurality of ridges extending substantially parallel with and adjacent to a first edge of said material, applying an adhesive coating to one side of said first edge of said material, overlapping a second edge of said material having a corrugated border over said adhesive coated side of said first edge of said material, and disposing said second edge of said material adjacent a plane surface of the first row of ridges on said first edge of said material to form a corrugated surface of equally spaced ridges and furrows.

2. The method of joining the edges of a piece of pliable and expandible corrugated material having plane

side surfaced ridges and furrows on both sides extending longitudinally of said material which comprises flattening a plurality of ridges extending substantially parallel with and adjacent to a first edge of said material, applying an adhesive coating to one side of said first edge of said material, forming a second edge of said material having a corrugated border along a plane surface of one side of a ridge of said material, applying an adhesive coating to the inside plane surface of said ridge, overlapping said second edge of said material over said adhesive coated side of said first edge of said material, and disposing said plane surface of said ridge of said second edge of said material adjacent the plane surface of the first row of ridges on said first edge of said material to form a corrugated surface of equally spaced ridges and furrows.

3. The method of joining first and second longitudinal edges of a tube formed from a piece of pliable and expandible corrugated material having plane side surfaced ridges and furrows on both sides extending substantially parallel with said longitudinal edges of said material and wherein said second longitudinal edge is formed along a corner of a bisected ridge of said material which comprises flattening a plurality of ridges formed adjacent said first longitudinal edge of said material, applying an adhesive coating to one side of the flattened surface of said first edge of said material and to the inside plane surface of the bisected ridge of said second edge of said material, overlapping said second edge of said material over said adhesive coated side of said first edge of said material, disposing said plane surface of said bisected ridge of said second edge of said material adjacent the plane side surface of said first row of ridges on said first edge of said material to form an outer tubular corrugated surface of equally spaced ridges and furrows, and applying heat and pressure to said first and second edges of said material to dry the adhesive and secure said longitudinal edges of said tube together to form a pliable and expandible tube.

4. A joint for sealing the longitudinal edges of a tube formed from pliable and expandible corrugated material having plane side surfaced ridges and furrows on both sides extending longitudinally of said tube comprising a first longitudinal edge of said material forming a plane surface, a second longitudinal edge of said material overlapping said first edge of said material, said second edge of said material being disposed adjacent the first row of ridges on said first edge of said material to form a corrugated surface of equally spaced ridges and furrows, and adhesive means provided on said plane surface of said first edge of said material to secure said longitudinal edges of said tube together to constitute a pliable and expandible tube.

5. A joint for sealing the longitudinal edges of a tube formed from pliable and expandible corrugated material having plane side surfaced ridges and furrows on both sides extending longitudinally of said tube comprising a first longitudinal edge of said material forming a plane surface, a second longitudinal edge of said material formed along a plane surface of one side of a bisected ridge of said material, said second edge of said material arranged to overlap said first edge of said material with the plane surface of said bisected ridge of said material being disposed adjacent the plane surface of the first row of ridges on said first edge of said material to form a corrugated surface of equally spaced ridges and furrows, and adhesive means provided on said flattened surface of said first edge of said material and on the inside surface of said bisected ridge of said second edge of said material to secure said longitudinal edges of said tube together to constitute a pliable and expandible tube.

6. A joint for sealing the longitudinal edges of a tube formed from pliable and expandible corrugated material having plane side surfaced ridges and furrows on both sides extending longitudinally of said tube comprising

ing a first longitudinal edge of said material forming a plane surface, the extremity of said first edge of said material being turned on itself, a second longitudinal edge of said material formed along a plane surface of one side of a bisected ridge of said material, said second edge of said material arranged to overlap said first edge of said material with the plane surface of said bisected ridge of said material being disposed adjacent the plane surface of the first row of ridges on said first edge of said material to form a corrugated surface of equally spaced ridges and furrows, and adhesive means provided on said flattened surface of said first edge of said material and on the inside surface of said bisected ridge of said second edge of said material to secure said longitudinal edges of said tube together to constitute a pliable and expandible tube.
